UNITED STATES PATENT OFFICE.

JOHN ALLEN HEANY, OF NEW YORK, N. Y.

ELECTRIC-ARC LAMP.

1,403,079.

Specification of Letters Patent. Patented Jan. 10, 1922.

Application filed June 11, 1917. Serial No. 174,103.

To all whom it may concern:

Be it known that I, JOHN ALLEN HEANY, a citizen of the United States, residing in the city, county, and State of New York, have 5 invented certain new and useful Improvements in Electric-Arc Lamps; and I do hereby declare the following to be a full, clear, and exact description of the invention, such as will enable others skilled in the art to 10 which it appertains to make and use the same.

The invention relates to electric arc lamps operating on very low wattages and at the ordinary commercial voltages and maintaining 15 high efficiencies even in the smaller sizes ranging as low as ten or fifteen candle power. To this end, the invention comprises a lamp, involving a container or envelope, preferably adapted for connection in the ordinary 20 incandescent lamp socket and containing an inert gas, preferably under diminished pressure, and two electrodes, between which the arc is established and maintained, connected to suitable lead wires, at least one of 25 which electrodes comprises a body portion of highly refractory oxide which is a non-conductor of electricity, but which incandesces at a high temperature, and having a terminal made of an admixture of refractory oxide and refractory metal, the body 30 portion of said electrode being surrounded by a coil of highly refractory metallic wire, which is connected to the terminal aforesaid, to serve as a ballast resistance, a luminant 35 body per se, and a heating element, the coacting electrode being normally in contact with the terminal of the other electrode and preferably mounted upon a thermostat which 40 operates to separate the electrodes to proper arcing distance, when the current passes through the lamp.

In the accompanying drawing, the figure illustrates a lamp embodying the preferred form of the invention.

45 Referring to the drawing, 1 indicates the globe or bulb of the lamp, which is preferably in the form usually employed in incandescent filament lamps, adapted for the usual socket connection, which bulb is exhausted of air and supplied with an inert gas, such as nitrogen, argon, or the like, preferably under diminished pressure. The bulb is provided with the usual form of glass neck 2, carrying the usual lead wires 50 connected to the lamp terminals, to one of which lead wires is attached by means of a

lead 3, a wire coil 4 made of highly refractory metal, such as tungsten, which coil surrounds and supports a rod-like element 5 of highly refractory non-conductive material, 60 such as thorium oxide, to the end of which is secured a terminal 6 formed of an intimate admixture of highly refractory oxide or oxides and finely divided and preferably highly refractory metal, such as tungsten, 65 dispersed throughout the same to render said terminal conductive. The electrode 5 is formed by mixing the refractory material of which it is made with a dissipating binder, moulding the plastic mass into the desired 70 form and then sintering the same to drive off the binder and harden the rod. The terminal 6 is formed in the same way and is provided with a depression having a diameter slightly larger than the diameter of the 75 electrode. The terminal is placed on the electrode so that the end of the electrode extends into the depression, after which the terminal is fused to the electrode. The end of the coil 5 is fused to said terminal 6. 80

The coacting electrode may, if desired, be formed substantially like that described, but preferably consists of a ball-like element 7 of highly refractory metal, such as tungsten or tungsten alloy, or a composition of the 85 same general character as terminal 6 of the opposite electrode. Said electrode 7 is secured to the lower end of the thermostat 8, which in turn is connected to the opposite lead wire of the lamp. The thermostat is 90 adjusted to hold the arcing ends of the electrodes normally in contact and to separate the electrodes to proper arcing distance when the lamp is operating.

When current is turned into the lamp, it 95 enters by way of lead 3, passes through the ballast and heating coil 4, thence to terminal 6, to electrode 7 in contact therewith, through the thermostat 8, back to the other terminal of the lamp. The effect of the passage of 100 the current is to highly heat the wire coil 4, raise the same to incandescence, and at the same time to raise the temperature of the refractory oxide rod 5 to the point where said rod becomes incandescent. The heat developed acting upon thermostat 8 causes the same to move electrode 7 away from the terminal 6 of the opposite electrode and establish an arc between said terminals. When the arc is established, it is maintained with 105 a steady brilliancy and quality approximating that of sunlight, and is augmented by the 110

incandescence of the refractory wire coil 4 and the rod-like body portion 5 of refractory oxide.

What I claim is:—

- 5 1. An arc lamp comprising a container, having suitable circuit connections, an electrode attached to one of said connections including a body portion formed of highly refractory oxide having a terminal of a mixture of refractory oxide and refractory metal and a heating and ballast coil of refractory metal surrounding said refractory material and connected to the terminal, a second electrode normally in contact with the terminal of the first electrode, and means for moving said electrodes apart to establish an arc therebetween. 30
- 10 2. An arc lamp comprising a container, having suitable circuit connections, an electrode attached to one of said connections including a body portion formed of highly refractory oxide having a terminal of a mixture of refractory oxide and refractory metal and a heating and ballast coil of refractory metal surrounding said refractory material and connected to the terminal, a second electrode normally in contact with the terminal of the first electrode, and means for moving said electrodes apart to establish an arc therebetween. 35
- 15 3. An arc lamp comprising a container, an electrode in said container formed of a mixture of a highly-refractory oxide and refractory metal, a second electrode normally in contact with said first electrode circuit connections for said electrodes including a ballast coil of refractory metal enveloping a core of refractory oxide, and means for moving said electrodes apart to establish an arc. 40
- 20 4. An arc lamp comprising a container, an electrode in said container formed of a mixture of a highly-refractory oxide and refractory metal, a second electrode normally in contact with said first electrode, circuit connections for said electrodes including a ballast coil of refractory metal enveloping a core of refractory oxide, a thermostat adapted to move said electrodes apart to establish an arc. 45
- 25

trode normally in contact with the terminal of the first electrode, and a thermostat adapted to move said electrodes apart to establish an arc therebetween. 50

In testimony whereof I affix my signature.
JOHN ALLEN HEANY.
